UNITED STATES PATENT OFFICE.

EDWARD J. MURPHY, OF GARY, INDIANA, ASSIGNOR OF ONE-HALF TO LEONARD B. GUMP, OF GARY, INDIANA.

ELECTRIC-RAILWAY SYSTEM.

1,112,548.

Specification of Letters Patent.

Patented Oct. 6, 1914.

Application filed November 3, 1913. Serial No. 798,395.

To all whom it may concern:

Be it known that I, EDWARD J. MURPHY, a citizen of the United States, and a resident of the city of Gary, county of Lake, and State of Indiana, have invented certain new and useful Improvements in Electric-Railway Systems, of which the following is a specification.

My invention relates to improvements in electrical railway systems and more specifically to means for transmitting the electrical energy from the conductor or feed wire of the system to the vehicle or railway car which travels along the track of the system.

15 The object of my invention is the production of a system wherein the overhead conductor or feed wire will be dispensed with and wherein the portions or parts of the system through which the electrical current 20 is conducted will be protected so as to obviate injury or death which might follow from contact with these parts when exposed.

A further object is the production of a system as mentioned which will be of simple 25 construction and efficient in operation.

Other objects will appear hereinafter.

With these objects in view the invention consists in the combinations and arrangements of parts hereinafter described and 30 claimed.

The invention will be best understood by reference to the accompanying drawings forming a part of this specification, and in which—

35 Figure 1 is a side elevation of a fragment of the track of an electrical railway system, embodying my invention, a vehicle or electric car being shown in dotted lines mounted upon said track, Fig. 2 is an enlarged detail 40 section taken on line $x-x$ of Fig. 1, Fig. 3 is an enlarged detail section taken on line $y-y$ of Fig. 1, Fig. 4 is an enlarged vertical section through one of the contact devices included in the construction, and Fig. 5 is a 45 transverse section taken on line $z-z$ of Fig. 4.

The preferred form of construction as 50 illustrated in the drawings comprises a conductor or feed wire 1 which extends along the railway track incased in a casing 2 of insulating material, said conductor extending beneath the ties 3 of the track upon which the rails 4 are mounted in the usual manner.

55 Spaced along the track at intervals and

mounted upon the ties 3 are electrical contact devices each of which comprises a cylindrical or circular housing 5 which is secured to the corresponding tie 3 by means of screws or other suitable fastening devices 6. 60 The upper end of housing 5 is provided with a switch cover 7 bolted to said housing as shown. Arranged at the upper end of said housing is a cap 8 provided with a depending stem 9 which projects loosely through a central opening provided in the cover plate 7 of said housing being mounted in a metallic bushing or lining 10 of an insulating ring 11 formed preferably of glass. The arrangement is such, as will be observed that cap 8 is insulated from the housing 5 and so that, in the operation of the system any electric current which may be conducted through said cap will not pass into said housing and thus be grounded. 70

Arranged below the lower end of stem 9 is a disk 12 of insulating material rigidly connected with said stem and held spaced from the lower end thereof by means of straps 13. The disk 12 is provided with a central opening lined with a metallic bushing 14 in which is mounted for free vertical movement the stem 15 of a soft iron disk 16. The arrangement is such that the member 16 will normally, by reason of gravity, assume a position at its lower terminal of movement, in which position the same will be insulated from the stem 9 of the cap 8 by reason of the insulating disk 12. Upon magnetization of the cap 8 and hence the stem 9 thereof said disk 16 will be attracted by said stem into contact with the lower end thereof so as to establish electrical connections between said parts. The lower end of stem 15 is connected through the medium of a flexible wire or connecting element 17 with a plate 18 which is mounted upon an insulating block 19 secured to the tie 3, said plate 18 being connected by a conducting element 20 with the conductor or feed wire 1, as 90 clearly illustrated in Fig. 4. The conductor element 20 extends through a casing 21 of insulating material in order to prevent grounding of the circuit. With the arrangement disclosed then, it will be seen that the 95 member 16 is in constant electrical connection with the conductor or feed wire 1, and that electrical connection between said conductor or feed wire and the cap 8 is normally broken, such electrical connection be-

100
105
110

ing effected only upon magnetization of said cap since, upon such magnetization, the member 16 will be attracted into contact with the stem 9 which completes the electrical connection between said cap and the conductor or feed wire.

Arranged at the under side of the vehicle or car 22 which is mounted for travel upon the rails 4 is an elongated contact member 23 upon the upper side of which are mounted electro-magnets 24 adapted to maintain the member 23 constantly magnetized. The contact member 23 is supported by posts 25 which are slidably mounted at their upper ends in guide members 26 secured upon and depending from the under side of the vehicle or car 22. The upper ends of the posts 25 are provided with transversely extending pins 27 which engage elongated slots 28 provided in the opposite sides of guide members 26, the arrangement being such that the posts 25 and hence the contact member 23 will be supported by said members 26 but in such a manner as to permit of upward movement thereof. Helical compression springs 29 coöperate with the posts 25 to normally hold the same and hence the contact member 23 at their lower terminals of movement. The guide members 26 are insulated from the car by means of blocks 30 of insulating material. The contact member 23 is preferably formed of a plurality of pivotally connected sections as shown so as to permit of flexing of the ends thereof during irregular or uneven movement of the car.

The contact member 23 is arranged to contact with the contact devices which are spaced along the track, the former being adapted to engage against the upper sides of the caps 8 of said contact devices during the travel of the car, said contact devices being spaced apart a distance slightly less than the length of the member 23 so that the latter will always be in contact with at least one of said contact devices during the travel of the car. As the member 23, which is in a state of magnetization by reason of the electro-magnets 24, contacts successively with the contact devices spaced along the track, each cap of said contact devices, as the same is engaged by said member 23, will become magnetized and thereby attract the corresponding member 16 into engagement therewith. When this is done the electrical connection of the conductor or feed wire, with the contact member 23 will be completed and thus the car will be supplied with its electrical current or energy to effect propulsion thereof. As the contact member 23 moves from engagement with the contact devices passed over, the caps 8, of said contact devices will demagnetize which effects release of the members 16 resulting in the breaking of the electrical connection between the con-

ductor or feed wire 1 and the caps 8. Thus, with this arrangement it will be seen that the portions of the system through which current is constantly passing or which are "alive" are constantly concealed so as to 70 avoid death or injury which might result from contact therewith. The annular depending flange of the cap 8 which surrounds the upper end of housing 5 serves as a protection in damp or rainy weather to prevent current leakage as will be understood by those skilled in the art. By yieldingly supporting the contact member 23, in the event of a depression in the track rails, said contact member will yield upwardly to compensate 80 for such depression, as will be readily understood. Also, through the vertically movable mounting of the cap 8 of the contact devices, in the event of an elevation in the track rails said cap will move upwardly through attraction of the member 23 into contact therewith. Thus with this arrangement a constant engagement of the contact member 3 with the contact devices is always insured.

While I have illustrated and described the preferred form of construction for carrying my invention into effect, this is capable of variation and modification without departing from the spirit of the invention. 95 I, therefore, do not wish to be limited to the precise details of construction set forth, but desire to avail myself of such variations and modifications as come within the scope of the appended claims.

Having described my invention what I claim as new and desire to secure by Letters Patent is:

1. A device of the kind described comprising a hollow body; an upper contact member slidably mounted in said hollow body; a guide carried by said contact member; a lower contact member mounted in said guide, both of said contact members having portions capable of becoming magnetized; and a magnet above said upper contact member adapted to draw the latter into engagement therewith and said lower contact member into engagement with said upper contact member, substantially as described.

2. A device of the kind described comprising a hollow body; an upper contact member slidably mounted in said body and insulated therefrom; a guide carried at the lower end of said contact member; a lower contact member insulated from and mounted in said guide, a portion of said lower contact member being of soft iron; a flexible electrical conductor connected with said lower contact member; and a movable magnet adapted to move over said upper contact member at varying distances therefrom, said magnet when over said upper contact member drawing the latter into engagement

therewith and said lower contact member into engagement with said upper contact member electrically connecting said contact members, substantially as described.

5 3. A device of the kind described comprising a hollow body having a top with a perforation therein; a contact member of soft iron having a stem slidably mounted in and electrically insulated from said perforation; a cap secured to said stem limiting the downward movement of said contact member; a guide carried by and depended from said contact member; a second contact member mounted in said guide and electrically insulated therefrom; a soft iron disk secured to the upper end of said last mentioned contact member; an electrical conductor having one end connected with the lower

end of said last mentioned contact member; and a magnet adapted to be positioned at 20 different distances from said first mentioned contact member, draw the latter into contact therewith and draw said second mentioned contact member into engagement with said first mentioned contact member establishing 25 electrical connection through said electrical conductor, contact members and magnet, substantially as described.

In testimony whereof I have signed my name to this specification in the presence of 30 two subscribing witnesses.

EDWARD J. MURPHY.
